UNITED STATES PATENT OFFICE.

HANS PETERSEN, OF DAVENPORT, IOWA, ASSIGNOR TO THE LINOGRAPH COMPANY, OF DAVENPORT, IOWA, A CORPORATION.

MOLD FOR LINOTYPE-MACHINES.

1,248,906.

Specification of Letters Patent. Patented Dec. 4, 1917.

Application filed October 20, 1916. Serial No. 126,765.

To all whom it may concern:

Be it known that I, HANS PETERSEN, citizen of the United States, residing at Davenport, in the county of Scott and State of Iowa, have invented certain new and useful Improvements in Molds for Linotype-Machines, of which the following is a specification.

The invention relates to improvements in molds, particularly adapted for use in connection with linotype machines.

In the operation of linotype machines, it is desirable to cast slugs of a wide variety of sizes to meet various conditions, and heretofore whenever it has been required to change one size slug to another, which frequently happens, it has been necessary for the operator of the machine to substitute liners of sizes different both in width and length for those previously used to make the mold cavity of a predetermined size to produce the desired slug. These changes require considerable time on the part of the operator, as well as a vast amount of labor, and it has also been found that a great variety of equipment must be stored to meet the conditions encountered by the printer.

The present invention aims to overcome the difficulties arising from the use of older types of devices, and in its broadest aspects provides a structure by which the operator may remain seated at practically all times and make the necessary changes with respect to the mold cavity to adapt the mold for casting slugs of any length and thickness with but the use of a single laterally adjustable liner entering the mold cavity from its open side. In carrying out the present invention the mold carrying wheel is preferably provided with a series of molds having body cavities tapering from front to rear and having channels in the cap portions thereof of different depths and tapering in the opposite direction, as shown in Figure 5, while the mold cavities of the different molds are the same sizes so that a single liner may be used for adjusting the portion of the predetermined mold cavity to remain open at the will of the operator, it of course being apparent that the deeper the grooves in the mold cap the wider the finished slug will be.

The invention also embraces the use of a movable liner that is tapered in formation, whereby the same may be readily inserted

within the mold cavity at a predetermined point to close a portion thereof to produce a slug of any length desired.

The invention more specifically comprehends the use of movable locking devices for holding a cast slug within the mold cavity when the liner is being withdrawn therefrom upon the receding movement of the mold wheel on its supporting dowel. The locking devices are automatically withdrawn from the mold cavity when the same is alined with the trimming knives, and these locking devices or pins are inserted within the mold cavity at a predetermined time after the liner has entered the said cavity so that certain of the locking devices are covered by the liner, which closes a portion of the cavity. The locking devices obviously prevent any movement of the slug, except when the mold cavity occupies a position in direct alinement with the trimming knives, at which time suitable automatic means withdraw the locking devices to release the cast slug.

The mold is not only designed to cast slugs of the straight type, but may also be used for casting slugs of the overhang type such as described in my copending application, Serial No. 119,226, as it is apparent that it is often desirable to use the slugs of an overhang type in preference to the ordinary straight slug.

In the accompanying drawings the preferred embodiment of the invention is illustrated, but it will of course be understood that many changes can be made to meet various conditions without departing from the spirit thereof.

In the drawings:

Fig. 1 illustrates a portion of the linotype machine carrying the adjustable liner, with the mold wheel and a mold supported thereby separated from the liner and occupying its normal position just previous to its advance to casting position.

Fig. 2 shows the parts in section when the mold wheel has been moved upon its dowels so that the liner has entered the mold cavity.

Fig. 3 shows the parts of the apparatus in their assembled positions with the mold cavity opened to its extreme length, the mold being forward or in casting position and the plunger 13 being disposed within the mold cavity.

Fig. 4 is a detail view of the locking devices and the actuating mechanism therefor with parts broken away.

Fig. 5 is a modified view of the mold wheel 5 in which the same is provided with two molds for producing slugs of different widths.

Fig. 6 is a view of the parts when the mold is in ejecting position, showing plungers or 10 pins withdrawn from the mold cavity.

Fig. 7 is a sectional view showing the mold cavity, the movable liner and its support.

Referring now more particularly to the drawings wherein like reference characters 15 indicate corresponding parts the numeral 1 designates a movable mold carrying wheel which may be of any approved construction and mounted with reference to the casting pot in any well known manner. The mold 20 wheel has one or more openings therein seating suitable mold portions, each mold comprising a body part 2 and a cap 3 which are secured within the openings in any approved manner, the mold slot being tapered from 25 front to rear, the mold cap 3 having a plurality of oppositely tapering transverse grooves therein for a purpose which will hereinafter appear. In Fig. 5 of the drawings I have disclosed a view of the mold 30 wheel, in which the same carries a pair of molds each having ribs or grooves therein of different widths so as to produce slugs of a thickness of from 6 to 16 points as the occasion may require upon the proper shifting 35 of the mold wheel, while the mold cavities are of the same size to be regulated by a single liner 5. The molds, whether one or more be used, are preferably composed of separable body and cap portions, fastened 40 together or to the mold wheel, or both, with an intervening stationary liner forming a third side wall of the mold cavity. The matrices, not shown, which are disposed adjacent the face of the mold when the same is 45 in a position for receiving a supply of metal, may be recessed to produce a slug of the overhanging character if desirable, this slug being of a construction such as cast in the apparatus disclosed in my pending applica- 50 tion, Serial No. 119,226.

To provide an adjustable supporting means for mounting the liner 5 so as to permit the same to be inserted at any desired point into the cavity of the mold for regulating that portion of the cavity which is to remain open to receive a supply of metal, a stationary portion 6 of the linotype frame has arranged therein an elongated slot or opening 7, provided with an entrance 8 on 55 one side and receiving an angular block 9, having a part disposed within the slot and retained against sidewise movement by frictional contact with the walls thereof and carrying at its outer end an upstanding support 10, receiving the tapering liner 5. The 60 65

liner 5 is recessed in its upper and lower surface so as to eliminate as much friction as possible when the same contacts with the mold cavity as the only portions thereof which engage the walls of the cavity are the 70 beaded or raised edges. The slot 7 is of a relatively great length so as to permit any adjustment of the block 9, which in turn carries the liner 5 entering the open side of the mold cavity and upon the adjustment of 75 the block the length of the cavity may be increased or diminished to form a cavity of a predetermined size.

The grooves in the mold preferably occur at regularly spaced intervals, coinciding 80 with standard printers' measures, the unit of which is the pica-em. The grooves in the mold would, therefore, occur either spaced one em apart in multiples or divisions thereof. The liner 5 is at all times carried by the 85 upstanding support 10 which is adjustable and appropriately moved to determine the length of the mold cavity. It will be understood that this forms one of the abutments for confining the line of matrices from which 90 the line is cast; the adjustment may be made in any well known manner. It will be understood that some variations in the construction are possible and that, for instance, the opposite matrix confining abutment, 95 termed the stationary vise jaw, designated by reference character 24, might also carry a liner similar to that carried by the adjustable jaw in which case the mold proper will consist merely in a body and cap portion 100 separately fastened in their proper position to the mold wheel without being connected together.

The liner normally occupies the position disclosed in Fig. 1 of the drawings, that 105 is out of contact with the mold parts, but when it is desired to cast a slug, the liner 5 and the mold wheel occupy the relative positions disclosed in Fig. 2, at which time the tapered liner is inserted within a portion of the mold cavity and a supply of molten metal is then injected within the cavity filling the same and casting a slug of a predetermined length and width. The liner 5 is tapered to permit the same to be readily 110 introduced into the similarly tapered cavity from its open end, and in order to prevent any accumulation of dirt or dust upon the surface of the liner support forming a portion of one side of the mold, channels 11 are 115 arranged therein which receive the dust or dirt accumulating around this portion of the mold that would ordinarily prevent a perfect seal between the jaw or liner support, and a portion of one side of the mold.

Arranged within a cavity in one side of the frame 6 and underlying the block 9, are a plurality of coil springs 12, bearing upon the under side of the block, these springs being slightly compressed when the 120 125 130

liner is inserted within a portion of the mold cavity to insure the holding of the same in its proper relative position while the liner enters the mold. When the mold 5 wheel and the liner are in the relative positions disclosed in Fig. 2, that is the mold wheel has been revolved and moved forward so as to permit the liner to enter a portion of one of the mold cavities, a supply 10 of molten metal is then forced into the cavity from a casting pot of any approved construction (not shown), filling that portion of the cavity as well as the recessed matrices lying adjacent thereto and the 15 tapering grooves disposed within the mold cap, it being observed that the grooves taper in a direction oppositely to that of the liner so that the slug cast in the mold will be substantially parallel on each side, even 20 though the mold cavity is tapered, and a slight trimming action will at all times produce a finished slug, that is rectangular in shape. The mold wheel can carry any number 25 of molds desirable, and in Fig. 5 I have shown the mold wheel as carrying a pair of molds. If a number of molds are used the grooves therein are of different depths, so that each mold will cast a slug of a different width, but the mold cavities 25 of the different molds are all of uniform dimensions 30 to permit a single liner to be used for varying the length of any number of mold cavities.

It is particularly desirable that some 35 means be employed for retaining the slugs within the mold during the withdrawal of the liner therefrom, and to this end I mount upon the mold wheel in any suitable manner a plurality of plungers 13 passing upwardly through the body of the mold and having attached to their lower ends coil springs 14, which springs are also secured to the body of the mold wheel and normally 40 tend to force the plungers upwardly so that their ends are disposed within the mold cavity. As the plungers are of the same specific construction and all operate simultaneously a detail description of only one 45 will be given. Carried by the elongated plunger 13 is a wide head 15 having a rounded face portion to which the coil spring 14 is attached. Suitably mounted upon the mold wheel beneath the body of the mold is a shiftable regulating bar 16 50 maintained in position by a bracket 17 rigidly fitted to the mold wheel and having upstanding arms 18 to retain this bar against sidewise movement, but to permit a horizontal adjustment thereof. The regulator bar 55 60 65 has arranged therein a plurality of sockets 20, corresponding in number to the number of plungers 13 and normally occupying a position away from the beveled heads carried by the plungers so that the straight lower edge of the regulating bar

will retain the plungers depressed against the tension of coil springs 14. However, upon the adjustment of the regulator bar to a position where the sockets overlie the beveled heads of the plungers 13, which occurs at a predetermined movement after the liner has been inserted within the mold cavity, the springs 14 exert an influence upon the plungers and raise the same upwardly so that the ends of certain of the plungers 70 project within the mold cavity, while the other plungers are held lowered by the liner if it occupies that portion of the cavity. When the plungers are within the cavity and the liner in an operative position, a supply 75 of molten metal is then injected within the mold filling the recesses in the matrices (not shown) and casting a slug of the predetermined size. The regulating bar is automatically actuated at a predetermined 80 time after the mold wheel has moved toward the liner upon its supporting dowels, the liner preventing the entrance of those plungers which would ordinarily enter that part of the mold cavity covered by the liner, 85 while the remaining plungers are permitted to enter the cavity. The operating means preferably consists of a pair of cams 21 and 22 projecting outwardly from the frame 7 and disposed in different vertical planes. 90 The mold wheel normally occupies a position as disclosed in Fig. 1, that is spaced from its liner, but when the same comes forward in any well known manner the liner enters a portion of the cavity, and then the 100 cam 22 working in the slot 23 of the regulating bar pushes the bar so that the openings therein overlie the beveled heads of the plungers, permitting the plungers 13 that do not underlie the liner to enter the mold 105 cavity. When the parts are in this position a supply of metal is injected into the mold cavity and a suitable slug cast.

After a slug has been cast in the mold cavity the mold wheel is then moved back 110 on its dowel pins, withdrawing the liner from the cavity, and during this withdrawing action the plungers 13 retain the cast slug within the cavity against the friction caused by withdrawing the liner, and the 115 mold wheel is then revolved past a suitable trimming means for shaping the bottom of the slug which is not shown, as it forms no part of the invention. The mold wheel when revolved until it has reached its normal position, that is to say a three-quarter turn from the casting position, is shown in Fig. 6. At this point the wheel again comes forward on its dowel pins, and during this movement the cam 21 contacts with the 120 inner edge of the slot 23 in the regulator bar shifting the bar in a direction opposite the movement given the bar by the cam 22, so as to move the sockets therein out of registry with the plunger heads 15 and withdrawing 125 130

the plungers from the cavity to permit the slug to be ejected by a suitable ejector and passed between the trimming knives for a final treatment.

5 Having briefly stated the invention the operation may be described as follows:

The parts of the mold normally occupy the relative positions shown in Fig. 6, at which time the liner 5 is withdrawn from

10 the mold cavity and the plungers 13 are in a lowered position, being retained in this condition by the regulating bar 16. When it is desired to cast a slug, the mold wheel carrying the mold revolves a quarter of a turn to the position shown in Fig. 1 and thence the mold wheel moves forward on a pair of dowel pins so that the liner 5 enters and closes a predetermined portion of the cavity as disclosed in Fig. 2 and Fig. 3.

15 20 During this shifting of the mold wheel and after the liner has entered the mold cavity to such an extent as to overlie the plungers 13, the cam 22 riding within the slot 23 in the regulator bar 16 moves the bar laterally to such a position as to allow the sockets

25 30 20 to overlie the heads of the plungers 13 so that part or all of the plungers are then raised by the tension springs 14 and enter the mold cavity. A supply of molten metal

35 30 is then introduced into the cavity and a suitable slug cast in that portion of the cavity not closed by the liner. The mold wheel and mold are then withdrawn from the liner 5, but during this withdrawing action of

35 40 35 the mold wheel from the liner 5, the upper ends of the plungers 13 still remain within the mold cavity for retaining the slug in place against the friction caused by the withdrawing of the liner on one end of the

40 45 40 slug. The mold wheel then revolves past a suitable knife (not shown) which trims the bottom thereof and the plungers 13 also

serve to retain the slug in its proper position during this trimming action and prevent the same from being pushed from the mold cavity. When the mold wheel has

45 50 45 reached its normal position, that is to say three quarters of a turn from the casting position, it again comes forward on its

50 55 50 dowel pins and the cam 21 engages the inner edge of the slot 23 in the regulator bar 16 moving the bar in a direction the reverse of the direction the bar is actuated by the cam 22 and causing the lower edge of the bar

55 60 55 to engage the heads of the plungers 13 and withdraw the plungers from the mold cavity to permit an ejector blade to force the slug from the mold so that it may be passed between the trimming knives.

60 65 60 While the preferred embodiment of the invention has been illustrated and described, it will of course be understood that the structure disclosed is capable of many changes without departing from the spirit of the invention.

Having thus described the invention, what I claim is:

1. A mold for linotype machines having suitable walls to provide a mold cavity, an adjustable liner for closing a predetermined portion of said cavity, a support for said liner, there being clearance channels disposed within said support, for the purpose described. 70

2. A mold for linotype machines comprising suitable mold parts adapted to provide a mold cavity, a liner for closing a portion of said cavity, and means for mounting said liner including a resiliently mounted member 9 connected to said liner to insure the proper positioning of said liner relative to the mold. 75

3. A mold for linotype machines comprising suitable mold parts adapted to provide a mold cavity having an open end, an adjustable liner for entering said open end for closing a predetermined portion of said cavity, and means for mounting said liner including a resilient member 12 interposed between the liner support and the frame of 80 the machine for retaining said liner in its proper position relative to the mold. 85

4. A mold for linotype machines comprising suitable mold parts adapted to provide a mold cavity, a liner for closing a predetermined portion of said cavity when the same is to receive a supply of molten metal, a movable part adapted to enter said mold cavity after the insertion of the liner therein, and means for withdrawing said part 95 from the cavity upon the shifting of the mold carrier when the cast slug is to be ejected from the mold, said means comprising a shiftable regulator bar, and cams for operating said bar upon a movement of the 100 mold carrier. 105

5. A mold for linotype machines comprising suitable mold parts adapted to provide a mold cavity, and having an adjustable liner for closing a predetermined portion 110 of said cavity when the same is to receive a supply of molten metal, movable devices adapted to enter said mold cavity after the insertion of the liner therein, and means for withdrawing said movable devices from 115 the cavity upon the shifting of the mold carrier when the cast slug is to be ejected from the mold including a regulator bar, said withdrawing means also comprising a cam adapted to engage the regulator bar 120 coöperating with said movable devices to shift the same. 120

6. A mold for linotype machines having a mold cavity therein, an adjustable liner to close a predetermined portion of said cavity when the mold is to receive a supply of molten metal, a plurality of movable members adapted to enter said mold cavity when the liner has been inserted therein, means for normally maintaining said mem- 130

bers whereby portions of the movable members that are not covered by the liner enter said cavity, and means for withdrawing said members from the cavity when the slug 5 is to be ejected from the mold comprising a regulator part coöperating with said members and adapted to be shifted to withdraw said members from the cavity.

7. A mold for linotype machines having 10 a mold cavity therein, a liner adapted to close a predetermined portion of said cavity when the mold is to receive a supply of molten metal, a plurality of movable members adapted to enter said mold cavity 15 when the liner has been inserted therein, means for normally maintaining said members whereby portions of said movable members that are not retained in a lowered position by the liner within the cavity enter 20 said cavity, and means for withdrawing said members from the cavity when the slug is to be ejected from the mold comprising a regulator part coöperating with said members and adapted to be shifted to withdraw 25 said members from the cavity, and means for shifting the regulator bar to withdraw the movable members from the mold cavity and permit the removal of the cast slug.

8. In a machine of the character described, the combination with mold supporting means, of a plurality of molds carried thereby, said molds having tapered cavities therein of uniform dimensions and being provided with channels tapering in a 35 direction opposite to the taper of the cavities, the said channels of the various molds being of different widths, in combination with a tapered liner for closing a portion of the cavity of any one of said molds.

40 9. A mold for linotype machines having a mold cavity tapered from front to rear, and grooves disposed in said mold and tapering in a direction opposite to the taper of the cavity and to substantially the same extent, 45 in combination with a tapered liner for closing a portion of said mold cavity.

50 10. A mold for linotype machines having a mold cavity tapered from front to rear, and grooves disposed in said mold and tapering in a direction opposite to the taper of the cavity and to substantially the same extent, 55 in combination with a tapered liner for closing a portion of said mold cavity, said liner being laterally adjustable, and entering the cavity when the mold is advanced to a casting position.

60 11. A mold for linotype machines having a stationary top, bottom and a side wall to provide a tapering mold cavity, in combination with an adjustable tapering liner adapted to close the remaining side of the cavity or a portion thereof when the mold is advanced to a casting position.

12. A mold for linotype machines having

suitable walls, and a casting cavity, a liner 65 for closing a portion of the cavity, there being a clearance channel disposed within the support for said liner, for the purpose described.

13. A mold for linotype machines comprising suitable mold parts adapted to provide a mold cavity having an open end, a liner for closing said open end and a predetermined portion of the cavity, and means for mounting said liner upon a portion 75 of the machine comprising resilient members upon which the liner supporting means rests for holding the same in its proper position.

14. A mold for linotype machines comprising suitable mold parts adapted to provide a mold cavity, a liner adapted to close a predetermined portion of said cavity, a movable member adapted to enter said mold cavity when the liner and mold are in a position to receive a supply of molten metal, and means for withdrawing said movable member from said cavity when the cast slug is to be ejected from the mold, said means comprising a regulator bar, and a 90 cam for shifting said bar, substantially as described.

15. A mold for linotype machines having a suitable mold cavity, movable members adapted to project into said cavity when the 95 mold is in a casting position, and means for withdrawing said members from the cavity at a predetermined time to permit the ejection of the cast slug, said members having rounded head portions, and a shiftable regulating bar provided with depressions therein coöperating with said rounded head portions.

16. A mold for linotype machines, having top, bottom and side wall to provide a tapering mold cavity, in combination with a tapering liner adapted to close the open side of the cavity, and a predetermined portion thereof when the mold is advanced to a casting 105 position.

17. A mold for linotype machines having a tapering mold cavity, in combination with a tapered liner for closing any desired portion of said cavity when the mold is advanced to a casting position.

18. In a machine of the character described, the combination with mold supporting means, of a plurality of molds carried thereby, said molds having tapered cavities therein, of uniform dimensions, in combination with a tapered liner for closing a portion of the cavity of either of said molds.

19. In a machine of the character described, the combination with mold supporting means, of a plurality of molds carried thereby, said molds having cavities of uniform dimensions and also being provided with channels, the channels of the different

molds being of various depths, in combination with a liner for closing a predetermined portion of the cavity of either of said molds.

20. In a machine of the character described, the combination with mold supporting means of a plurality of molds carried thereby for casting slugs of different widths in combination with a liner for closing a predetermined portion of the cavity of either of said molds upon the adjustment of the mold supporting means to a casting position.

21. In a machine of the character described, the combination with a mold supporting wheel, of a pair of molds carried thereby for casting slugs of different widths, in combination with a liner for closing a portion of the cavity of either of said molds upon the adjustment of a mold supporting wheel to a casting position.

22. In a machine of the character described, the combination with a mold supporting wheel, of molds carried thereby, said molds having tapered cavities of uniform dimensions and being provided with channels for forming ribs upon a cast slug, the channels of the different molds being of various depths, substantially as described.

23. In a machine of the character described, the combination with a mold supporting wheel, of molds carried thereby, said molds having tapered cavities of uniform dimensions and being provided with channels for forming ribs upon a cast slug, the channels of the different molds being of various depths, in combination with a liner for closing a predetermined portion of the tapered cavity of either of said molds.

24. A mold for linotype machines having suitable walls forming a mold cavity, a liner for said cavity, a support for the liner, having a clearance opening formed within said support for the purpose described.

25. A mold for linotype machines having suitable walls forming a mold cavity, a liner for closing a portion of said cavity, a sup-

port for said liner having a horizontal clearance channel therein for the purpose described.

26. A mold for linotype machines, comprising suitable mold parts adapted to provide a mold cavity, a liner for the cavity, and means for mounting said liner including a resilient member adapted to insure proper positioning of the liner relative to the mold. 50 55

27. A mold for linotype machines, comprising suitable mold parts adapted to provide a mold cavity, a liner for closing a portion of the cavity, and means for resiliently mounting said liner whereby the same is 60 maintained in proper position relative to the mold.

28. A mold for linotype machines, comprising suitable mold parts adapted to provide a mold cavity, a liner for closing a portion of said cavity when the same is moved to a casting position, a movable device adapted to enter the mold cavity, and means for withdrawing said device from the mold cavity after a slug has been cast and is to 70 be ejected from the cavity, said means comprising a regulating bar, and cams operating with said bar for shifting the same in different directions depending upon the movement of the mold. 75

29. A mold for linotype machines, comprising suitable mold parts adapted to provide a mold cavity, a liner for closing a portion of said cavity when the same is moved to a closing position, a movable device adapted to enter the mold cavity, and means for withdrawing said device comprising a regulator bar, and a cam co-operating with said bar for shifting the same to correspondingly move said device. 80 85

In testimony whereof I affix my signature in presence of two witnesses.

HANS PETERSEN.
